UNITED STATES PATENT OFFICE.

WILBER J. PINE, OF OSHKOSH, WISCONSIN.

COMBINATION METAL-WORKING MACHINE.

Application filed August 12, 1918. Serial No. 249,425.

To all whom it may concern:

Be it known that I, WILBER J. PINE, a citizen of the United States, residing at Oshkosh, county of Winnebago and State of Wisconsin, have invented new and useful Improvements in Combination Metal-Working Machines, of which the following is a specification.

My invention relates to improvements in combination metal working machines.

The object of my invention is to provide an improved machine capable of performing the functions of a lathe, a milling machine, a shaper, and a grinder.

In the drawings:

Figure 1 is a side elevation of a machine embodying my invention.

Figure 2 is a similar view, partly in vertical section, exposing the carriage, and with the head partially broken away to expose the carriage operating mechanism.

Figure 3 is an end elevation showing the head column and associated parts.

Figure 4 is an end elevation showing the tail column and associated parts with the tail stock removed.

Figure 5 is a detail view of the reversing mechanism for the longitudinally movable carriage.

Figure 6 is a fragmentary plan view of the head stock and back gear mechanism showing the connections for operating the grinding wheel.

Figure 7 is a fragmentary rear view showing a portion of the driving connections of the grinding mechanism.

Like parts are identified by the same reference characters thruout the several views.

My invention includes all of the essential features of an ordinary engine lathe, viz:— the head and tail columns 1 and 2, the head stock 3, tail stock 4, bed 5, carriage 6, cross head 7, manual and automatic means for reciprocating the carriage and cross slide,

including the manually operable cranks 8 and 9 and the power driven shafts 10 and 11, the latter being operatively connected with the spindle 13 by any suitable power transmitting mechanism located in the gear box 12, (Figures 1 and 3), a suitable back shaft 14, with ordinary gear connections with the spindle, and suitable clutch mechanism being also employed in conformity with established practice.

But it will be observed that the lathe bed 5 is supported by screws 20 and 21 and is

arranged to slide in suitable guideways formed in the head and tail columns 1 and 2. The screws 20 and 21 have threaded bearings in posts or columns 24, whereby a rotation of the screws will raise or lower them, thereby lifting or lowering the bed. The screws may be actuated by means of a manually operable crank 27, the motion of which is transmitted to the respective screws thru the intermeshing gear wheels 29 and 30, shaft 31, and bevel gear wheels 32 and 33, the latter being mounted upon the upper ends of the screws 20 and 21 respectively, (Figure 2).

The power shaft 11 drives the main feed screw 36, shaft 11 being flexibly jointed at 40 and 41, universal or double knuckle joints with telescope shaft being employed, in order that the table with the feed screw 36 may be raised and lowered without disconnecting the power.

Shaft 10 is similarly universally jointed at 42 and 43. This shaft is employed to reciprocate the carriage and cross slide when the device is being operated as a lathe, motion being transmitted in one direction to the rack engaging pinion 45 thru the bevel gear wheels 46 and 47, (Figure 5), pinion 48 carried by wheel 47, gear 49 driven by pinion 48, gear 49' which is adapted to be manually engaged by handwheel 51 with gear 49 thru clutch disk 50, and gear 52 upon which is mounted rack gear 45. The rack gear 45 can also be operated manually thru hand wheel 8 which carries gear 8' engaging with gear 52. The cross slide 7 may be mechanically driven by using hand wheel 151 to move gear wheel 152 to a position where it will enmesh with gear 49. Gear 152 is also engaged with and adapted to drive gear 153 which may be turned manually by the crank 9. This gear in turn drives 154 and 155, the latter being fast to the cross feed screw 156.

But it will be observed that the pinion 46 is mounted upon a sleeve 62 connected with a shifting slide 63 adapted to engage stops 64 and 65 at the respective ends of the field of movement of the carriage. These stops may be supported from the shaft 10, as shown in Figure 5, there being sufficient clearance to allow them to rotate with the shaft. It is not material, however, whether they are supported on the shaft or from any fixed point on the machine. The slide 63 is mounted on the carriage apron, and,

assuming it to be moving in the direction of the arrow in Figure 5, it is obvious that, when the slide 63 strikes stop 65, it will be shifted in a direction to carry the beveled pinion 46 out of contact with the bevel gear wheel 47 and to simultaneously carry another bevel pinion 67 into close proximity with the bevel gear wheel 47 on the opposite side of shaft 48.

19 In order that the bevel pinions 46 and 67 may be automatically advanced into mesh with bevel gear 47, I employ the T-shaped trip 70 connected with the apron by the link rods 71 and 72, at the pivot pins 73 and 74, the link rods being formed in extensible sections which tend to spread under the pressure of compression springs 75, the arrangement being such that the springs will be compressed when the head of the T-shaped member 70 is at the line of centers thru the pivot pins 73 and 74. Upon crossing said line, the springs will react and co-operate with the stop 65, (or 64), in shifting the slide 63 to its proper position with one of the pinions 67, (or 46), in engagement with the bevel gear wheel 47, the pinions being then held in such position by spring pressure until the carriage has traveled in the opposite direction to the limit of its stroke 30 and into engagement with the opposing stop for another shifting movement of the slide 63. This results in an automatic reverse of carriage suitable for grinding arbors.

35 The object of adjusting the table vertically is to facilitate the use of the machine as a milling machine, and increase or diminish the swing of lathe and clearance. It will be observed that the spindle is provided 40 with a chuck receiving nose 80, exteriorly threaded and also socketed, whereby it is adapted to receive a chuck having a threaded socket or a centering point 81. The head stock is also extended upwardly far enough 45 to receive an overarm 83 provided with a brace 84 adjustably mounted thereon and adapted to provide an outboard bearing for an arbor, (one end of which would be engaged by the spindle nose 80). Owing to the 50 fact that the bed is vertically adjustable, the carriage longitudinally movable, and the cross slide 7 transversely movable, it is obvious that all of the adjustments and movements required for milling operations are 55 obtainable. When not in use, the brace 84 may be rotated upon the overarm 83, and the latter retracted if desired, as is common in milling machine practice. Therefore 60 neither the overarm nor the brace will interfere with lathe work or grinding operations.

65 In order that the device may be adapted for use as a planer, I have provided a center slide 90 having notches 91 in its upper surface. The carriage is transversely bored and 70 adapted to receive a cross rod 92 having a

fin or key-wing 93 adapted to fit in any one of the notches 91 of the slide 90. By disconnecting the carriage from the power operated driving mechanism, i. e., by releasing a clutch, as is common practice in lathe operation, to connect and disconnect gears 49 and 49', I am able to reciprocate the carriage in a series of quick strokes adapted for planing or grinding operations thru the medium of the slide 90. The chuck is supported in the usual manner from the face 88 of the column, this being provided with an ordinary circle groove concentric with the spindle, as indicated at 89, whereby the chuck may be rotatively adjusted. The tool will, of course, be supported upon the slide in the usual manner.

75 Slide 90 may be operated from the slow gear 95 of the back gear mechanism thru pinion 96, shaft 97, gear wheels 98 and 99, (45 degree gears), crank pin 100, bearing member 101, lever 102, and link bar 103, the latter connecting the upper end of lever 102 with slide 90. Lever 102 is pivoted to the foot of the head column 1 at 105. Crank 80 pin 100 is connected with the gear wheel 99 and carries a roller bearing member 101 which travels in a slot 107 formed in the lever 102. The crank pin 100 is preferably 85 adjustably mounted in a radially extending slot 109, whereby this crank pin may be moved toward and away from the center of gear wheel 99, thereby varying the length of stroke transmitted to the slide 90 and the carriage. It will, of course, be understood 90 that crank pin 100 will be anchored in the desired position of adjustment in the slot 105 by an ordinary clamping set screw or any other suitable means.

95 Pinion 96 is adapted to be shifted on shaft 97 into and out of engagement with the driving member 95 on the spindle, (and which constitutes the driven member of the back gear train), by means of a manually operable crank 112 located exterior to the column 1 but having a stud shaft 13 extending thru the wall of the column and connected with a gear shifting arm 115 within the column, as clearly shown in Figure 2. Therefore, gear wheel 96 may be readily shifted 100 to an inoperative position, and the carriage may, with equal facility, be released from slide 90 by withdrawing key-rod 92, after which, the carriage may be reconnected with the feed screw 36 or with the reciprocating 105 mechanism driven by shaft 10.

110 Motion is transmitted from the spindle to the screw actuating shaft 10 thru ordinary gearing within the gear box 12 as indicated by dotted lines in Figure 3. A belt 120 also indicated by dotted lines transmits motion from the spindle to shaft 11. These connections are adapted to transmit motion at reduced speed.

115 But for operating the grinding wheel 122 120

(Figures 3 and 6), a high speed motion is transmitted from special spindle pulley 124 thru belt 125, pulley 127, belt 129, operating over pulleys 130 and 131, and a shaft 132 extending thru the tubular back gear shaft 133, the shaft 132 having a flexibly jointed shaft extension 134 leading to and operatively connected with, the arbor of this grinding wheel. Pulleys 127 and 130 are carried by a swinging arm 128, and a lever 140 has a forked short arm 141 loosely engaging with the pulley shaft 142, whereby these pulleys, (127 and 130), may be swung about the axis of shaft 132 as a center to 15 distend or slacken belt 129. When the belt is slack no motion will be transmitted.

It will be understood that the grinding wheel is mounted upon the lathe carriage. When the grinding wheel is thus operated in connection with the automatic carriage reversing mechanism, above described, it will be obvious that work mounted on the lathe centers, (i. e., arbors, for example), can be ground with the accuracy of the 20 micrometer adjustments commonly provided for engine lathes.

In the construction above described, I am enabled to utilize various changes of speeds and feeds of an engine lathe for the 25 various purposes set forth, and I have therefore provided a combination machine which is practical for a wide range of work, but which will occupy no greater floor space than an ordinary engine lathe. I have also 30 provided means whereby all of the various mechanisms may be driven from a single source of power, operatively connected in common, and subject to all micrometer adjustments commonly used.

40 I claim:

1. The combination with the head column, table and carriage of a lathe, of a swinging lever in the head column, power connections adapted to oscillate said lever, and means 45 for operatively connecting the carriage to the lever.

2. The structure set forth in claim 2, in which the lever is pivotally supported near the base of the column, and in which the 50 actuating connections of the lever are adjustable lengthwise thereof to vary the length of stroke of the carriage.

3. The structure set forth in claim 2, in combination with a carriage actuating slide 55 detachably connected with the carriage, and which constitutes a portion of the connections between the lever and carriage.

4. The combination with the head column, table and carriage of a lathe, of a swinging lever in the head column, power connections adapted to oscillate said lever, a carriage 60 actuating slide detachably connected with said carriage and constituting a portion of the connections between said lever and said 65 carriage, said slide having a series of

notches and a transversely movable key carried by said carriage and having a wing adapted to be engaged in any one of said notches to adjustably connect said carriage and said slide.

5. The combination with the head column, table and carriage of a lathe, of a swinging lever pivotally mounted adjacent its lower end within the head column, power connections adapted to oscillate said lever, a 70 carriage actuating slide, a link connecting said lever and said slide, said slide having a series of notches, and a transversely movable key carried by said carriage and having a wing adapted to be engaged in 75 any one of said notches to adjustably connect said carriage and said slide.

6. In a lathe mechanism provided with a table, longitudinally movable carriage, spindle, and back gear mechanism, the combination of a slide supported by the table, and detachably connected with the carriage, slide actuating mechanism adapted to reciprocate the slide and carriage along the 80 table, and separate carriage actuating and reversing mechanism operative independently of the slide.

7. The structure set forth in claim 7, in which the slide actuating mechanism is driven from the gear mechanism of the 85 lathe.

8. The structure set forth in claim 7, in which the separate carriage actuating mechanism is detachably connected therewith, and adapted for use when the slide and 90 carriage are disconnected.

9. A combination lathe, milling machine, and planer mechanism provided with a carriage supporting table, means for vertically adjusting the table and carriage, carriage 100 operating mechanism, a flexible jointed shaft for operating said mechanism, and means associated with said shaft for reversing said carriage operating mechanism.

10. A combination lathe, milling machine, and planer mechanism provided with a carriage supporting table, means for vertically adjusting the table and carriage, carriage 110 operating mechanism, a flexible jointed shaft for operating said mechanism, and means associated with said shaft for reversing said carriage operating mechanism in combination with means for reciprocating the carriage relatively rapidly independently of said flexible jointed shaft.

11. The combination with a lathe, provided with a carriage adapted for reciprocating movement, of a lever pivoted in the lathe column, and detachably connected with the carriage, and means connected with the driving mechanism of the lathe for swinging said lever to reciprocate said carriage.

12. The combination with a lathe, provided with a carriage adapted for reciprocating movement, of a lever pivoted in the lathe column, and detachably connected with the carriage, and means connected with the driving mechanism of the lathe for swinging said lever to reciprocate said carriage.

cating movement, of a lever pivoted in the lathe column, and detachably connected with the carriage, and means connected with the driving mechanism of the lathe for 5 swinging said lever, said lever operating means being also detachably connected with the driving mechanism of the lathe.

13. The combination with a lathe bed, a carriage mounted to slide thereon, a carriage operating mechanism, of auxiliary carriage operating mechanism adapted to be detachably connected with the carriage, and means for operating the same from the driving mechanism of the lathe in relatively 10 quick strokes as compared with the ordinary operation of the carriage.

14. The combination of a lathe mechanism, including a longitudinally movable, and a transversely movable work support, 20 together with a head stock, tail stock, and a spindle, provided with direct drive and back gear mechanism, of motion transmitting connections adapted to transmit motion from the spindle to actuate the work sup-

port in two directions, and alternative 25 means connected with the back gear mechanism for reciprocating the work support in relatively quick strokes.

15. A combination engine lathe, milling machine and shaper comprising a head 30 stock, an over-hanging arbor support adjustably connected with said head stock, a bed, means for raising and lowering said bed, a carriage movably mounted upon said bed, power operated feeding means for 35 feeding said carriage longitudinally and transversely of said bed and adapted to be detached from said carriage, and independent means for giving said carriage relatively rapid longitudinal reciprocatory motion.

In testimony whereof I affix my signature in the presence of two witnesses.

WILBER J. PINE.
